Inventor:
Carl J. Shuler,
By *John Lawrence*
Attorney.

UNITED STATES PATENT OFFICE.

EARL J. SHULER, OF NEW ORLEANS, LOUISIANA, ASSIGNOR TO RAIL WELDING AND BONDING COMPANY, OF EAST CLEVELAND, OHIO, A CORPORATION OF DELAWARE.

MOLD FOR ATTACHING RAIL BONDS.

Application filed November 22, 1918, Serial No. 263,723. Renewed November 6, 1925.

To all whom it may concern:

Be it known that EARL J. SHULER, a citizen of the United States of America, residing at New Orleans, in the parish of Orleans and State of Louisiana, has invented certain new and useful Improvements in Molds for Attaching Rail Bonds, of which the following is a specification.

My invention relates to improvements in molds for attaching electrical bonds to railway rails, and has for its object the provision of a structure which is better adapted to permit the cast-welding of copper bonds to the ends of rails, preferably by the negative terminal of an electric arc, such as is described in the patent to J. C. Lincoln, No. 1,183,992, May 23rd, 1916.

In said patent there is shown a carbon mold adapted to receive the ends of a copper bond; in which mold the head of each terminal is separately secured by cast-welding the same directly to the respective ends of the electrically united rails.

My present invention contemplates a composite carbon and copper-faced mold, wherein the heads or terminals of the bond may be more readily and effectively cast-welded, than in any prior mold. Briefly described, the device of my invention comprises a frame removably attachable to the rail ends, wherein a copper-bottomed form is provided for receiving the renewable carbon mold-block. Two sliding copper members are adapted to close upon the ends of the bond, when the same are inserted within the mold. The features of this device may best be explained by referring to the accompanying drawings, wherein:—

Fig. 1 is a plan view showing the device and two rail ends operatively associated.

Fig. 2 is a view thereof in side elevation.

Fig. 3 is a cross-sectional view through the rail, and an end view of the device.

Fig. 4 is an enlarged view of the frame with the mold-block removed therefrom.

Fig. 5 is a face view of the device and

Fig. 6 is a fragmentary view of the attaching clip. Throughout the several figures of the drawings I have employed the same character of reference to indicate similar parts.

It is assumed that the rail ends *a*, *b*, are to be electrically united, over which the attaching clips *c*, *c'* are positioned to hold the frame *d* of the mold with its copper bottom-

members *d'* closely in engagement with said rails; said frame being supported by the spring member or bar *c''*. The copper slides *e* are inwardly pressed by a spring *e'* and are held in place by the reversible mold-block *f* of carbon, which has spaces or openings upon either side wherein the terminals of the bonds are adapted to be cast-welded. These spaces *f'* register with the openings between the members *d'*, through which the ends of the bond *g* protrude and are held by the slides *e*. Clip *c* is hinged at *c''*, Fig. 6.

The advantage of providing a carbon mold-block, whereby oxidation of the copper is minimized, obviously obtains in the structure of my invention. In addition, however, the copper members, forming in this instance only the bottom faces for the mold, serve as heat-conducting members which rapidly radiate the intense heat of the electric arc whereby the copper of the terminal is fused with the surface of the rail end to produce a head upon each end of the bond. This adjacent body of copper, not only assists materially in perfecting a better cast-welded terminal for the bond, but serves in addition, to stabilize the arc, which preferably is the negative carbon-electrode, during the fusion of the bond, the surface of the rail end, and the additional copper ordinarily supplied to complete the body of the cast welded terminal. The fused copper immediately solidifies in spaces *f'*.

My invention contemplates the provision of a mold having a wall or walls of maximum heat-conducting properties, such as copper, wherein the cast-welding operation may be most advantageously effected; said mold optionally having a carbon wall or walls, as well, for securing the well-known advantages to be attained thereby.

The copper members *d'*, it will be observed, are positioned so that they are engaged directly with the bodies of the rail heads, and in consequence serve to convey by conduction, a portion of the heat from the arc, which although extremely intense, is relatively small in amount. In addition to serving as a support for the mold block, the metal framework, as well as the copper portions associated therewith, supplies the important function of a chill member for the molten metal of the bond terminal, whereby the heat is rapidly conducted away

and radiated by the body of the frame. This frame is normally in contact with both heads of the bond during the welding operation and protects the body of the laminated bond from overheating and fusing by the action of the arc. Moreover, said arc is steadied in its action by the surrounding walls of the mold block, so that more efficient results are secured than when my improved appliance is not used. I may term the structure shown and described a chill-shield member.

Having now described the preferred embodiment of my invention, I claim as new and desire to secure by Letters Patent, the following:

1. A mold for attaching rail bonds having a bottom portion formed of copper and an upper refractory portion, said copper portion being adapted to be engaged directly with the body of the rail for conducting away the heat, substantially as set forth.

2. A mold for attaching rail bonds having a bottom portion formed of copper and an upper refractory portion, said copper portion being adapted to have the bond head cast-welded directly thereon and positioned to be engaged with the body of the rail as well for dissipating the heat, substantially as set forth.

3. A mold for attaching rail bonds having a bottom portion open to receive the end of the bond and closely embrace the same and an upper recessed carbon portion; the said bottom portion being formed of copper and adapted to be engaged directly with the rail for conducting away the heat, substantially as set forth.

4. A mold for attaching rail bonds, comprising a reversible carbon mold block and a separable two-part conductive member formed of copper, said copper member being open at the bottom to embrace the end of the bond and adapted to engage the body of the rail when in use, substantially as set forth.

5. A mold for cast-welding rail bonds, comprising a receptacle for the ends of the bond; said receptacle being provided with walls of copper and of carbon, substantially as set forth.

6. In an appliance for cast-welding electric bonds upon rail ends, the combination with a metallic frame, of a carbon mold block mounted thereon, a laterally extending spring member supporting the frame, and rail clips terminating said member, substantially as set forth.

7. In an appliance of the class described, the combination with a mold member, of a bowed spring member supporting the same, and clips for attaching the latter to the rail-ends; one of which is hinged to fit more readily over the rail, substantially as set forth.

8. In an appliance of the class described, the combination with a mold member recessed to receive the end of an electric bond; the same having walls of highly conductive properties as to heat, and walls having reducing properties, of means for removably attaching the appliance to the rail-ends, substantially as set forth. 70

9. In an appliance of the class described, the combination with a mold member recessed to receive the inserted end of a bond; the same having refractory walls of high thermal conductivity, of a metallic member also of high thermal conductivity adapted to engage and hold said bond, substantially as set forth. 75

10. A mold for attaching rail bonds, comprising a recessed mold member having two-part relatively movable wall-members formed of metal possessing high thermal conductivity adapted to engage and hold the inserted end of the bond and having carbon mold walls, and means for removably attaching the device to the rail ends, substantially as set forth. 80

11. A device used in securing rail bonds to rails, comprising in combination a bar, means to engage a rail to hold the device in working position and means secured to the bar to engage and hold a bond terminal in position on a rail and simultaneously chill the terminal and shield the heating flame or arc while installing the bond terminal, substantially as set forth. 85

12. A device used in securing rail bonds to rails, comprising in combination a bar, means adapted to secure the device in working position, and a chill-shield member as described, substantially as set forth. 90

13. A device used in welding rail bonds to rails, comprising in combination a bar, means to hold the device in working position, and metallic means secured to the bar adapted to chill the bond, substantially as set forth. 95

14. A device used in welding rail bonds to rails, comprising in combination a bar and a chill-shield member secured thereto for the intent and purpose described. 100

15. The combination with a rail and a rail bond positioned thereon for welding, of a device adapted to chill the bond terminal and protect the welding arc from atmospheric changes, substantially as set forth. 105

16. The combination with a rail and a rail bond positioned thereon for welding, of a device adapted to rapidly conduct the heat from the terminal of the bond and protect the bond from the destructive action of the heating flame, substantially as set forth. 110

17. A device used in attaching bonds to rails, comprising in combination a resilient member, separate means for engaging each terminal of a rail bond and moving independently of each other in a lateral direc- 115

120

tion with respect to the rail members, and means securing the above named members in position on the rail, substantially as set forth.

- 5 18. A device used in bonding rails, comprising in combination a body member, a metallic chill-shield member for conducting and absorbing heat from the bond terminal and preventing vertical air drafts about 10 the terminal and provided with means for preventing horizontal air drafts about the terminal, and means for securing the above parts in position on a rail, substantially as set forth.
- 15 19. The method of welding rail bonds to rails consisting in positioning the bonds to the rail and applying them to a metallic device adapted to rapidly absorb and conduct heat from the terminal and protect the 20 terminal from atmospheric changes and then applying an electric arc to the terminal and rail to bring them to a proper temperature to melt attaching metal.
- 25 20. The method of attaching rail bonds, substantially as herein set forth, comprising the support of a bond in a heat-conducting and radiating member, adjusting the end of the bond to the rail end, applying the electric arc to said bond and rail locally to set 30 cure fusion, meantime effectively conducting away the excess of heat, and applying additional molten metal to the bond to form a terminal integral therewith and with the rail.
- 35 21. The method of attaching electric rail bonds, substantially as herein set forth,

comprising supporting the bond terminals in a closely embracing heat-conductive metallic frame work containing copper and carbon portions, engaging the ends of the 40 bonds with the rails, applying the electric arc to said bond and rails locally to secure fusion, meantime conducting away the excess of heat by means of said copper portions, protecting the arc against disturbance, 45 and supplying additional molten metal to the bond to form terminals integral therewith and with the rails.

22. Means for attaching electric rail bonds, comprising a recessed metallic framework of high conductivity adapted to engage the end of the bond and protect the body thereof from excessive heat, upstanding refractory walls surrounding the terminal wherein it may be welded upon the side 50 of the rail, and means for temporarily positioning the appliance and bond upon the rail ends, substantially as set forth.

23. Means for attaching electric bonds to rail ends, comprising a metallic support of high conductivity adapted to engage the end of the bond and protect the body thereof, upstanding refractory walls between which the terminal may be welded upon the end 55 of bond and the side of the rail by a partially enclosed arc and means for temporarily positioning the appliance and bond upon the rail, substantially as set forth.

In testimony whereof I do hereto affix my signature.

EARL J. SHULER.
